CLAIM

The ornamental design for a swimsuit bottom with opening, as shown and described.

DESCRIPTION

FIG. 1 is a perspective view of a swimsuit bottom with opening showing the design;

FIG. 2 is a rear elevational view of the swimsuit bottom with opening of FIG. 1;

FIG. 3 is a front elevational view of the swimsuit bottom with opening of FIG. 1;

FIG. 4 is a top plan view of the swimsuit bottom with opening of FIG. 1;

FIG. 5 is a bottom plan view of the swimsuit bottom with opening of FIG. 1;

FIG. 6 is a left elevational view of the swimsuit bottom with opening of FIG. 1; and,

FIG. 7 is a right elevational view of the swimsuit bottom with opening of FIG. 1.

The dash-dash broken lines in the drawings depict portions of the swimsuit bottom with opening that form no part of the claimed design. The dash-dot broken lines in the drawings define boundaries of the claim and form no part thereof.

1 Claim, 3 Drawing Sheets
